FOLDING CRIB AND STROLLER

Theodore F. Schmidt, Elmhurst, Ill.

Application July 25, 1947, Serial No. 763,721

11 Claims. (Cl. 5-98)

1

This invention relates in general to a folding crib and stroller which is capable of assuming three different positions; in a raised or extended position as a bed or stroller; in a partially lowered position as a play pen, and in a completely collapsed condition for carrying or storing it.

An important object of the invention is to provide a folding structure which is both light and strong so that it may be easily carried and moved.

A further object is to provide a folding structure which has no projecting parts when folded so that it occupies no more space than the extended dimensional area of the frames.

A further object of the invention is to provide means actuated from either side for releasing the parts which hold the structure in its extended positions and to change from one position to another.

A still further object of the invention is to provide a folding structure of this kind in which a mattress support is suspended from an upper frame by fabric sides which adapt the structure to fold compactly, eliminating unnecessary parts for collapsing and extending it into its various positions.

Other objects of the invention will appear in the specification and will be apparent from the accompanying drawings illustrating the invention in which:

Fig. 1 is a perspective view of a folding crib and stroller in accordance with this invention, in its raised or extended position;

Fig. 2 is a perspective view of the structure shown in Fig. 1 in a partially lowered or intermediate position to provide a play pen;

Fig. 3 is a perspective view of the structure in its completely collapsed or folded condition;

Fig. 4 is a sectional plan view taken just above the wheels in the extended position of Fig. 1;

Fig. 5 is a sectional view taken on the line 5-5 of Fig. 4.

In folding cribs heretofore provided, the folding structures are usually so heavy and cumbersome that they are not easily portable when folded and some portion of the folding structure usually extends beyond the confines of the frame itself to make a cumbersome structure which is difficult to carry, and it also occupies considerably more space than the dimensional area of the bed and closing frame.

The present invention overcomes these objections by providing a folding structure which collapses within the outer confines of the frames so that no portion thereof projects beyond the

outer area of the frames, thus limiting the size of the folded structure to the actual rectangular dimensions of the structure in its extended position.

5 An added convenience of the present invention is the provision of tripping means operable from either side of the crib in changing it from a crib to a play pen or from a play pen to its collapsed position.

10 Referring now more particularly to the drawings, an upper frame 10 of wood, metal, or any other suitable material has fabric sides 11 and ends 12 secured to it by fastening tacks 13, the sides and ends being a continuous strip of canvas or other suitable material, or separate pieces, if desired. The lower edge of each side and end are similarly secured to a bottom frame 14 by tacks 15, the frame having cross slats 16 for supporting a mattress 17 within the sides and ends.

15 20 The enclosed mattress structure is supported by a wheeled frame at the bottom and below it by means of a folding parallelogram connected at each corner of the upper frame.

The wheeled frame comprises an axle 18 at each 25 end with a wheel 19 freely rotatable at each end of the axle. Extending between the opposite axles are connecting rods 20 which hold the axles suitably spaced apart. Mounted on the rods intermediate their ends is a cross piece 21 which extends to the outer sides of the frames, the rods preferably extending through the cross piece.

30 At each side of the cross piece is a latch bar 22 having a projection 23 at the end of the cross bar. Each latch has a pivot 24 at its side of the cross bar located at the opposite side of the mid-portion of the cross piece from which the projection extends at the end.

35 Locking bars 26 and 27 are connected to the opposite axles 18 by hinges 28 so that they may swing downwardly, and these bars are formed with projections 29 and 30 which overlap below the cross piece 21. A screw 32 is inserted through the overlapping projections and through the cross piece with a fastening nut 33 at the upper side and with a coil spring 34 interposed between the head of the screw and the lower projection 30 tending to hold the locking bars against the underside of the cross piece.

40 In order to insure the movement of both locking bars when either one of the latches 22 is operated, a plate 36 is attached to the upper sides of the bars 26 and 27 by fastening screws 37 inserted through slots 38 in the plate.

45 50 In the tops of the locking bars are locking notches 40 and 41 each adapted to engage a cross

bar 42 of the supporting parallelogram structure at the ends. Each cross bar 42 has openings adjacent its ends for mounting it to slide upon the bars 20 and to be seated in the notch 40 or 41 and to be entirely disengaged from the notches when the crib is in a collapsed position.

Each cross bar 42 is connected at each end to a lever 44. Intermediate its ends it is pivoted to a cross lever 45, the lower end of which is mounted to rotate upon the axle 18, and the upper end of the lever is connected to one end of a link 46, the other end of the link being connected intermediate the ends of a lever 47, one end of the lever 47 being pivoted to the upper end of lever 45 and the other end of the lever being pivoted to the side of the frame 13 at the adjacent corner thereof. Between the connected ends of the lever 44 and the link 46 is a cross piece 50. Extending between opposite sides of the crib frame so that the cross bars 42 and 50 at each end of the crib are connected by the lever 44, thus insuring the joint operation of the two parallelogram structures at each end of the crib.

In operation, assuming the structure is in its extended position as shown in Fig. 1, the upper frame 13 is raised substantially above the supporting wheel frame suspending the lower frame 14 by means of the sides and ends 11 and 12, and the supporting parts are locked in this position by the engagement of the cross bars 42 in the notches 40 near the outer ends of the locking bars 26 and 27.

To lower the crib, one of the latch bars 22 is operated by engaging its projection 23 at the end of the cross piece 21, preferably by pressing the projection 23 with the toe of the foot. This depresses the overlapping ends 29 and 30 of the locking bars against the spring 34, thus freeing the notches 40 of the locking bars from engagement with the cross bars 42 so that by pressing downwardly upon the frame 13, the bars 42 are moved inwardly upon rods 20 into engagement with notches 41, thereby holding the supporting structures in the lowered or intermediate position as shown in Fig. 2.

In this lower position, the crib is located substantially upon the floor or any other surface upon which it is supported, being separated therefrom only by the relatively flat wheel supported frame. In the raised position, the structure may be used as a crib or bassinet moved about upon the wheels 19, and in its lowered or intermediate position, it may be used as a play pen.

When it is desired to fold or collapse the structure to a position as shown in Fig. 3, either of the latch bars is again tripped by engagement of the toe in the condition as shown by Fig. 2, whereupon the cross bars 42 are disengaged from the slots 41, and the cross bars 42 are moved inwardly on top of the locking bars 46 without engagement with any of the notches thereof. In this position, the parallelogram supporters are folded closely and compactly together, the arrangement of the links and levers is such that they fold together and do not project beyond the ends of the upper and lower frames 13 and 14.

In the collapsed position, the fabric sides and ends 11 and 12 fold inwardly, overlapping the edges of the mattress 17 but not projecting materially therefrom, the folded structure being only slightly thicker than the mattress and the flat supporting frame and wheel being mounted for movement upon the wheels 19 if desired. In the collapsed position, the structure is readily

portable and occupies a minimum of space so that it may be conveniently stored or shipped in a small package.

While I have thus described the invention as a folding crib and stroller, it should be regarded by way of illustration and example rather than a restriction or limitation of the invention as various changes in the construction and arrangement of the parts may be made without departing from the spirit and scope of the invention.

I claim:

1. A folding crib structure, comprising an upper rectangular marginal frame, a lower mattress supporting frame suspended from the upper frame by flexible sides and ends, a running gear frame below the mattress frame of substantially the same outer dimensions as the upper frame, and a supporting collapsible folding structure at the sides and adjacent the ends of the frames, each comprising a parallelogram supporting means having four pivoted links, three of said links having portions extending beyond the configuration of the parallelogram, one of said extending portions being pivotally connected to a corner of the upper frame, another of said extending portions being pivotally connected to a corresponding axle of the running gear frame, a cross bar fastened to said third extending portion, and means in connection with the bottom frame for engaging said cross bar.

2. In a folding crib, an upper rectangular supporting frame, a lower mattress frame connected to the upper frame by fabric sides and ends, a bottom rectangular supporting frame having wheeled axles at the ends, parallelogram supporting means at the sides adjacent the ends of the frames, each of said parallelogram supporting means comprising four pivoted links, three of said links having portions extending beyond the configuration of the parallelogram, one of said extending portions being pivotally connected to a corner of the upper frame, another of said extending portions being pivotally connected to a corresponding axle of the bottom frame, a cross bar fastened to the third extending portion, and means in connection with the bottom frame for engaging the cross bar in different positions to hold the upper supporting frame at different levels and the parallelogram supporting means being foldable compactly at the sides inwardly from the ends of the frames when the structure is collapsed.

3. A folding crib having a rectangular wheel supporting frame and an upper rectangular supporting frame, a parallelogram supporting means adjacent each corner of the frames, each of said supporting means comprising four pivoted links, three of which have portions extending beyond the configuration of the parallelogram, one of said extending portions being pivotally connected to a corner of the upper frame, another of said extending portions being pivotally connected to a corresponding axis of the wheel supported frame, a cross bar fastened to the third extending portion, and means in connection with the wheel supporting frame for engaging the said supporting means for holding it and the crib at two different levels and in collapsed condition upon the running gear frame, the ends of the said supporting means foldable inwardly at the sides of the frames without projecting beyond the ends thereof.

4. In a folding crib construction, an upper rectangular marginal frame and a mattress frame supported therefrom by flexible sides and ends,

a wheeled supporting frame having end axles connected by parallel side bars, a folding support at each corner adjacent the ends of the frames comprising parallelogram supporting means, each having four pivoted links, three of said links having portions extending beyond the configuration of the parallelogram, one of said extending portions being pivotally connected to a corner of the upper frame, another of said extending portions being pivotally connected to a corresponding axle of the wheeled frame, a cross bar connecting the folding means of each end and locking means connected to the axles and movable into and out of engagement with the cross bars for engaging the cross bars in different longitudinal positions for holding the crib at different heights and the crib being collapsible with the supporting means upon the frames.

5. In a folding crib structure, an upper rectangular marginal frame and a mattress frame foldably connected thereto by fabric sides and ends, a wheeled rectangular supporting frame comprising end axles connected by parallel bars, foldable supporting means adjacent the corners of the frames connected to the sides of the marginal frame and to the end of each axle, a cross piece connecting the foldable supporting means at adjacent corners, and guided for sliding movement by the parallel bars, a locking bar connected to each axle and extending inwardly therefrom, each locking bar having notches therein for engaging the cross bar, spring means tending to hold the locking bars upwardly together, and means intermediate the ends of the wheeled supporting frame engageable from either side of the frames for depressing the inner ends of the locking bars for releasing the cross piece from its engagement with the notches thereof in collapsing and extending the crib.

6. The combination with a folding crib having an upper rectangular marginal frame and a lower mattress supporting frame suspended therefrom by fabric sides and ends, of a wheeled rectangular supporting frame having end axles connected by parallel side bars, a collapsible folding structure at the sides adjacent each end of the frame, said folding structure being pivotally connected at the bottom to one axle and pivotally connected at the top to the side of the marginal supporting frame at the end thereof, a cross bar mounted to slide upon the parallel cross bars of the wheeled supporting frame and connected at its ends to the collapsible folding structure, a locking bar pivoted to each axle and extending inwardly in overlapping relation having notches in the upper side to engage the cross bar of its respective end, spring means tending to hold the locking bars in upwardly biased operative relationship, and foot engageable means at the center of the wheeled supporting frame projecting at opposite sides thereof and movable downwardly to depress the overlapping ends of the locking bars for freeing the engagement of the cross bars of the collapsible folding structures.

7. In a folding crib structure, an upper marginal frame and a mattress supporting frame connected thereto by fabric sides and ends, a wheeled supporting frame having end axles connected by parallel supporting bars, a collapsible folding structure at each end of the frames pivotally connected at the top to the ends of the marginal frame and pivotally connected at the bottom at the opposite ends of the axle and including a cross bar at the bottom slidable upon the parallel bars which connect the axles, a locking bar

hingedly connected to each axle having upper notches to engage the cross piece of the folding structure, said locking bars extending inwardly from the axles and having the free ends thereof overlapping, a supporting cross-piece mounted upon the parallel side bars between the axles, bolt means extending through the cross piece and including a spring disposed below said overlapping ends tending to press the inner ends of the locking bars upwardly against said supporting crosspiece, and latch bars pivotally mounted at each side of the cross piece, each latch bar being disposed on one side of the longitudinal center and extending over said center to the end of the cross piece, said latch bar having a portion projecting beyond said cross piece end, and means engaged by both of the latch bars for depressing both of the locking bars to free the cross bars of the folding structure from engagement with the locking bars.

8. A folding crib structure, comprising a wheeled supporting frame having axles spaced apart by longitudinally disposed members and a cross piece supported centrally between the axles, a locking bar hinged to each axle and extending inwardly below the cross piece with notches in the upper surface of each locking bar, resilient means carried by the cross piece to press the inner ends of the locking bars upwardly, latching means disposed on either side of said cross piece and having an extension at each end thereof for engagement by the toe of the foot, means for depressing the inner end of each locking bar when either latch is depressed, a flat folding crib structure having an upper marginal frame, a flat folding link and lever structure connected at the top to the marginal folding frame and at the bottom to the end of the adjacent axle, and a cross piece at each end secured to said link and lever structure mounted to slide upon said longitudinal members of the wheeled supporting frame and engageable with the notches of the locking bars.

9. In a folding crib, an upper rectangular frame, a lower mattress frame supported thereby and connected by foldable fabric side and ends, a wheeled rectangular supporting frame having axles spaced apart by parallel side bars, a cross piece fixed on the side bars, a locking bar hinged to each axle and extending below the cross piece, the locking bars having transverse notches, a cross bar having openings through which the side bars extend, said cross bar being engageable in the notches, resilient means tending to hold the locking bars upwardly, a parallelogram folding structure adjacent each end of the sides having four pivoted links of which three have portions extending beyond the configuration of the parallelogram, one of the extending portions being pivotally connected to a corner of the upper frame, another of the extending portions being pivotally connected to a corresponding axle of the bottom frame, and a third extending portion connected to one end of said cross bar, means attached to the cross piece and projecting at each end thereof and each operable for engaging both locking bars and pressing them downwardly to disengage both locking bars from the notches to release the folding structures for collapsing and extending movements.

10. A three position folding crib having an upper marginal frame and a spaced mattress frame with a flexible connection for suspending it, a wheeled supporting frame having axles spaced apart by parallel side bars, a locking bar

hinged to each axle extending longitudinally of the frame and with transverse upper notches, a cross piece fixed on the side bars, releasing latches pivoted on each side of the cross piece and extending to the outsides of the parallel bars for operating the locking bars, and connected link and lever folding mechanisms at each end of the frames connected at the top to the marginal frame and at the bottom to the running gear frame and disposed at all times close to the confines of the frames, the two mechanisms at one end of each frame being connected by a crossbar which engages the notches of the locking bar, the latches being operable from either side of the crib for releasing both locking bars to move the 15 crib from one position to another.

11. A folding crib in accordance with claim 10 in which the locking bars each have two notches for holding the crib frame in a raised position

and in a lowered position, and being disengaged from the locking bar in a collapsed position, in which the mattress frame and the flexible connection are compressed together between the marginal frame and the supporting frame.

THEODORE F. SCHMIDT.
